SWITCH

John C. Ponstingl, Pittsburgh, Pa., assignor to
Westinghouse Electric Corporation, East Pitts-
burgh, Pa., a corporation of Pennsylvania

Original application August 6, 1948, Serial No.
42,785. Divided and this application April 28,
1950, Serial No. 158,831

2 Claims. (Cl. 200—87)

1

This invention relates, generally, to electro-
magnetic devices and more in particular to an
electromagnetic switch or relay.

This application is a division of the applicant's
now abandoned copending application Serial No.
42,785, filed August 6, 1948, entitled Switch and
assigned to the same assignee as this invention.

One object of this invention is to provide an
improved type of electromagnetic switch or relay
comprising coil means, core means, a movable
armature and contact structure actuated by the
armature, which is simple in its elements and
positive in operation.

A more specific object of this invention is to
provide a relay of the type described having an
improved armature structure.

Another specific object of this invention is
to provide a relay of the type referred to which
embodies an improved contact assembly.

A further specific object of this invention is
to provide a relay of the class referred to em-
bodying an improved type of hinge structure
and biasing means for the armature.

The foregoing statements are merely illustra-
tive of the various aims and objects of this in-
vention. Other objects and advantages will be-
come apparent upon a study of the following dis-
closure when considered in conjunction with the
accompanying drawings, in which:

Figure 1 is a side view of an electromagnetic
switch or relay shown partially in section which
embodies the principles of this invention, the
switch or relay being illustrated in its ener-
gized position;

Fig. 2 is a view similar to Fig. 1 in which the
electromagnetic switch or relay is shown in de-
energized position;

Fig. 3 is a view looking at the front of the
relay;

Fig. 4 is a bottom view of the relay, and

Fig. 5 is a detailed view of the armature as-
sembly illustrating the armature in its minimum
air-gap position.

Referring now to Figs. 1, 3 and 4 of the draw-
ing, the electromagnetic switch or relay is ar-
ranged for mounting on a panel board such as
1 as illustrated in Fig. 1. In this mounting
the base 2 of the relay which is preferably of
magnetic material is secured to the panel 1 by
any suitable means. The relay comprises two
cores 3 and 4 which are spaced transversely of
the bottom plate 2 forming a magnetic circuit
which, as viewed in Fig. 4, is substantially of
U-shaped configuration. Coils 5 and 6 are dis-
posed, respectively, about the cores 3 and 4 form-

2

ing an electromagnetic structure. Plates 7 and 8
which are of magnetic material are fastened re-
spectively by means of screws 9 and 10 which
thread into the free extremities of the cores 3
and 4. The bottom ends of plates 7 and 8, as
viewed in Figs. 1 and 4, are bent at right angles
towards the base of the relay and upon the inner
edges of the faces formed by the bent-over sur-
face portions or faces 11 and 12, a bracket 13
of non-magnetic material of substantially U-
shaped configuration is secured, the extremities
14 and 15 of the sides of the U-shaped bracket
13 being bent downwardly as better viewed in Fig.
2, forming another pair of surfaces at right an-
gles to the surfaces 11 and 12 of the plates 7
and 8.

The armature assembly 16 of the relay com-
prises a member 17 which is formed of a single
piece of non-magnetic material to provide faces
18 and 19 in the same plane as the surfaces 11
and 12 and to provide a second pair of faces 20
and 21, respectively, in the same plane as the
surfaces 14 and 15 of the bracket 13. Flat leaf
springs 22 and 23 are respectively secured to
faces 11, 18 and faces 12, 19, while flat leaf
springs 24 and 25 are respectively secured to the
faces 14, 20 and 15, 21 forming two pairs of
crossed leaf spring assemblies at transversely
opposite sides of the armature assembly. The
point of intersection of the springs, when viewed
edgewise, substantially forms the hinge line of
the crossed leaf spring assembly.

The armature is biased away from the core
structure to the position viewed in Fig. 2 by a
biasing spring assembly which includes a stud
26 threadedly engaging the integrally formed leg
27 which is disposed substantially at right angles
to the leg 17 of the armature assembly. The
stud 26 thus substantially parallels the leg 17
of the armature assembly and projects down-
wardly as viewed in Fig. 1 across the hinge line
of the crossed leaf spring assembly. A nut 28
having a circumferential groove is threaded over
the extremity of the stud 26 and a tension spring
29 is attached between a hole 30 in U-shaped
member 13 and the circumferential groove in the
nut 28 to exert a bias on the stud 26 and, hence,
upon the entire armature assembly. As illus-
trated, the nut 28 lies below the hinge line of the
crossed leaf spring assemblies. As a consequence,
a moment arm exists with respect to the hinge
line which, due to the biasing effect of the ten-
sion spring 29, exerts a counterclockwise torque
55 about the hinge axis of the armature assembly

affording a normal position of the relay or switch as illustrated in Fig. 2.

It will be appreciated upon inspection of this assembly that the biasing effect upon the armature assembly is varied by changing the moment arm through the simple expedient of changing the position of the nut 28 along the stud 26, thus it is unnecessary to change the tension of the biasing spring or make other complicated adjustments in an effort to change the calibration of the relay.

The magnetic member 31 of the armature assembly is disposed between the leg 17 of the non-magnetic member and the leg 32 thereof which is formed as an integral extension of the leg 27 and at right angles thereto to lie parallel to the leg 17. The legs 32 and 17 have the coaxially disposed clearance holes 33 and 34, respectively, formed therein and a bolt 35 having clearance in these holes and having its head abutting the leg 32 is inserted therethrough. The armature 31 is equipped with a securely attached threaded bushing 36 in threaded engagement with the bolt 35 and a compression spring 37 is disposed between the armature 31 and the leg 32 affording an armature bias to the right as viewed in Fig. 1 to secure the assembly in position and maintain the head of the bolt 35 in secure frictional engagement with the leg 32. The spring 37 maintains the separation between armature 31 and the leg 32 through which bolt 35 is inserted and functions as a flexible spacer. When bolt 35 is turned either clockwise or counter-clockwise the relative position of armature 31 is changed and spring 37 conveniently acts as the spacer means to hold armature 31 rigid with respect to leg 32. As illustrated in Fig. 1, the armature is set substantially in its maximum air-gap position, and as seen in Fig. 3, the armature straddles the pole assembly to form a magnetic circuit thereacross. Clearance holes 33 and 39 in the armature clear the heads of the screws 9 and 18 which secure the pole plates 7 and 8 to the extremities of the cores 3 and 4, respectively. In the detailed sectional view of Fig. 5, the armature is illustrated in its minimum air-gap position. This setting is accomplished by the simple expedient of rotating the bolt 35 in the proper direction. It should be noted at this point that adjustment of the air gap between the armature and the cores 3 and 4 in no way disturbs the setting of the contacts since the contacts for the switch are carried at the free extremity of the leg 17 which remains undisturbed by movement of the armature 31.

The contact assembly of the electromagnetic switch or relay comprises a pair of opposed stationary contacts 41 and 42 which are mounted on terminal strips 43 and 44, respectively. Terminal strips 43 and 44 are secured within an arc-box structure 45 of an electrically insulating material and this arc-box structure is secured to the base 2 by means of a U-shaped support 46, the arc-box structure being carried between the extremities of the U-shaped support. This U-shaped support is preferably a permanent magnet or if not a permanent magnet is preferably formed of magnetizable material having small permanent magnets at the extremities to produce a magnetic flux for controlling the arc which is struck at the contacts upon opening thereof. Alternatively a non-magnetic U-shaped member may be employed having permanent magnet pieces attached adjacent the extremities of the sides thereof to produce the arc controlling magnetic field. The

use of a permanent magnet eliminates the need for a blowout coil and its circuit connections.

The movable contacts 47 and 48 are mounted on opposite faces of a U-shaped flat spring member 47a at the extremity of the leg 17, as viewed, for movement back and forth in contact engaging position between the respective stationary contacts 41 and 42. One side of the U-shaped spring member is threaded near the base thereof to receive a screw 49 having clearance through a hole in the leg 17. The other side of the U-shaped member is secured to the leg 17 by means of a screw 50 having clearance through the leg 17 and the said one side of the U-shaped spring member and which threads through the opposite side of the U-shaped spring member 47a. The screw 50 is provided with an enlarged head which in the instant case is formed by securing washer 51 to the head of the screw 50 to rotate therewith, the washer 51 being of sufficient diameter to extend radially beneath the head of the screw 49. Thus the distance D between the contacts 47 and 48 may be changed as desired by the simple expedient of loosening the screw 49 and turning the screw 50 to change the contact gap G. Once the desired setting of the contacts 47 and 48 is achieved, the screw 50 is locked in the selected position by retightening of the screw 49.

While a preferred embodiment of this invention has been illustrated in the drawings and described in the descriptive disclosure, it will be appreciated by those skilled in the art that various detail changes in the structure herein considered may be made without departing from the spirit and scope of this invention. Accordingly, it is intended that the foregoing disclosure be considered only as illustrative of the principles of this invention and not interpreted in a limiting sense.

I claim as my invention:

1. A relay comprising, in combination, a coil, a core for said coil, an armature, a non-magnetic movable member supporting said armature adjacent said core for motion to and from said core, a pair of oppositely disposed stationary contacts, a resilient U-shaped member having contacts at the extremities of the sides thereof, means securing one side of said U-shaped member to said non-magnetic movable member with the contacts thereof disposed between said oppositely disposed stationary contacts, adjusting means connected between said non-magnetic movable member and the side of the U-shaped member remote from said non-magnetic movable member for adjustably biasing the side of said U-shaped member, remote from said non-magnetic movable member, towards and away from the side thereof secured to said non-magnetic movable member, for adjusting the spacing between said contacts at the extremities of the sides of the U-shaped member, and locking means connected with said adjusting means for releasably locking said adjusting means in preselected positions.

2. A contact assembly comprising, in combination, a pair of oppositely disposed stationary contacts, a U-shaped spring member having a pair of contacts one on each outside face of the sides of the U-shaped member adjacent the extremities of said sides, a movable member, a screw clearing through said movable member and threading into one side of the U-shaped member thereof to support the U-shaped member with the contacts thereof disposed for motion between the stationary contacts, a second screw having a large head assembly, the edge of which passes beneath the head of the first mentioned screw to be clamped

thereby, said second screw clearing through said movable member and said one side of said U-shaped member and threadedly engaging the remaining side of said U-shaped member.
